J. D. Cochran,

Pick Handle,

No 43,638,

Patented July 26, 1864.

UNITED STATES PATENT OFFICE.

JOHN D. COCHRAN, OF KERN RIVER, CALIFORNIA.

IMPROVEMENT IN PICKS.

Specification forming part of Letters Patent No. 43,638, dated July 26, 1864.

To all whom it may concern:

Be it known that I, JOHN D. COCHRAN, of Kern River, county of Tulare and State of California, have invented a new and Improved Pick, called "Cochran's Pick;" and I do hereby declare that the following is a full, clear, and exact description of the construction and operation of the same, reference being had to the annexed drawings, making a part of this specification.

The nature of my invention consists in providing a cheap and substantial pick, suitable for mining or other purposes, so constructed that it will possess the greatest strength at the point where the greatest strain takes place, and also to obviate the difficulty arising from the shrinking and swelling of the pick-handle, which difficulty is largely complained of by miners on the Pacific coast.

To enable others skilled in the art to make use of my invention, I will proceed to describe its construction and operation.

I make my pick of iron, pointed with steel, constructed in separate sections, with shoulders at the end of either section, or with sockets in the handle, or shoulders in the handle, as the case may be. A band of iron is placed over the base of the handle, constructed either with sockets or shoulders. To prevent shaking

or loosening of the pick, I place india-rubber between the joints. A beveled clasp, while in a heated state, is placed over the base of the pick and driven on, which draws the two arms firmly together. The band of iron is now driven down upon the flanges F F, and the construction is completed, forming a perfect tool without shake or tremble.

Figure 1 in the drawings is a view of the pick with all its parts adjusted. A is the beveled clasp or dog. B B are the arms. C is the sliding band. D is the joint or socket-band. F F are the flanges of the pick. E is the handle.

Fig. 2 is a sectional view. A is the beveled clasp or dog. B B are the arms. C C are bands; D, socket-band; E, handle; F F, flanges.

Fig. 3 is the pick-head; A, dog or clasp. B B are arms; C C, band.

What I claim as my invention, and desire to secure by Letters Patent, is—

A pick constructed as described, substantially as and for the purpose specified.

JOHN D. COCHRAN.
